MANUFACTURE OF STRING OR TWINE

Filed Aug. 10, 1925

UNITED STATES PATENT OFFICE

FRED N. LA CHAPELLE, OF BEVERLY, MASSACHUSETTS, ASSIGNOR TO UNITED SHOE MACHINERY CORPORATION, OF PATERSON, NEW JERSEY, A CORPORATION OF NEW JERSEY

MANUFACTURE OF STRING OR TWINE

Application filed August 10, 1925. Serial No. 49,327.

This invention relates to the manufacture of string or twine and is illustrated herein with reference to an improved method of manufacturing twine which may be used to 5 produce a hard, stiff paper twine with a smooth surface.

Twisted paper twine has been manufactured for many years and has been used for various purposes. In accordance with the 10 purpose for which it was intended, the twine, as an incident to its manufacture, has been impregnated with a greater or less amount of sizing material, commonly glue. This 15 serves to make the twine hard and stiff enough for any of the purposes for which it has heretofore been used, for example for the manufacture of furniture.

It is an object of the present invention to provide an improved method applicable to the 20 making of harder, stiffer twine than that of the prior art, with a smooth surface, adapted, for example, to be used as fastenings, as disclosed in Letters Patent of the United States, No. 1,729,169, granted Sept. 24, 1929, on an 25 application filed in the name of the present inventor. In accordance with this object, the herein disclosed method of manufacturing twine may be said to be characterized by the application of a supplemental surface 30 coating of sizing to twine which has been previously impregnated with sizing. As disclosed herein dry, twisted paper twine previously impregnated with glue is passed through a bath of liquid glue, whereby the 35 twine is given a supplemental surface coating of glue, and any surplus glue is removed by a suitable stripper after which the twine is dried. This produces twine having a smooth surface and harder and stiffer than has heretofore been manufactured. While such twine 40 may be used for other purposes, it is well adapted to be used for driven fastenings as set forth in said Letters Patent.

With the above and other objects and features in view, the invention will now be described with reference to the accompanying drawing and pointed out in the claims.

The drawing discloses mechanism adapted to be used in the manufacture of twine in 45 accordance with my improved method.

In the drawing, twisted paper string or twine 12, which earlier in its manufacture has been impregnated through and through with sizing, for example glue, and then dried, is passed from a reel 14 over a suitable idler 16 55 into a bath of liquid glue 18 contained in a receptacle 20. A pulley 22 serves to guide the twine through the bath of glue. From the bath of glue the string or twine 12 passes over an idler 24 and through a stripper 26 60 to remove any surplus glue from the twine before the glue has a chance to harden. The surplus glue thus removed flows from the stripper 26 down a plate 36 and into a receptacle 38. From the stripper 26 the twine 65 with the moist supplemental coating of glue thereon passes through a drier 28 which evaporates the moisture from the glue. From the drier 28 the twine with its supplemental surface coating of glue now hardened passes 70 to a reel 30 on which it is wound.

The bath of liquid glue 18 in the receptacle 20 may conveniently be kept hot by an electric heating unit 32. The stripper 26, which may be of any suitable material, may, if desired, also be kept warm by an electric heating unit 34. It should be understood, however, that this is not always essential. Similarly drier 28 is illustrated as heated by an electric heating unit 40, though other sources 80 of heat may be used.

While this apparatus is well adapted to the carrying out of the method of the present invention, it should be understood that it is disclosed herein primarily for purposes of 85 illustration. My new method is in no way dependent upon the use of this particular apparatus since evidently the apparatus may take various forms.

Summarizing, in practising the novel 90 method as herein disclosed, dry, twisted paper twine, which has been previously impregnated with glue, is passed from a reel 14 through a bath 18 of hot liquid glue where a supplemental surface coating of glue is applied to the twine, any surplus glue is removed by a stripper 26, and the twine is heated and the surface coating of glue dried 95 by a drier 28.

Having described the invention, what I 100

claim as new and desire to secure by Letters Patent of the United States is:

1. That improvement in methods of manufacturing twisted paper twine which comprises impregnating the twisted paper twine through and through with glue, drying the twine, passing the impregnated and dried paper twine through a bath of glue, thereby applying a supplemental surface coating of glue to the twine, and thereafter removing any surplus glue from the surface of the twine before the glue hardens.
  2. That improvement in methods of manufacturing paper twine which comprises passing paper twine previously impregnated with glue through a bath of glue so as to apply a supplemental surface coating of glue to the twine, and then stripping any surplus glue from the surface of the twine before the glue hardens.
  3. That improvement in methods of manufacturing paper twine which comprises passing twisted paper twine which has previously been impregnated with glue through a bath of glue, thereby applying a supplemental surface coating of glue to the twine, stripping any surplus glue from the twine, and heating the twine to dry the coating of glue upon the twine.
- 30 In testimony whereof I have signed my name to this specification.

FRED N. LA CHAPELLE.
